HOT-BLAST STOVE

Andrew Bowland, Mount Lebanon, Pa., assignor to
 William M. Bailey Company, a corporation of
 Pennsylvania

Application August 3, 1942, Serial No. 453,353

3 Claims. (Cl. 263—19)

1

This invention relates to hot-blast stoves of the type used to heat the blast of an iron blast-furnace, the object being to provide the synthetic rubber industry with a stove of this type capable of operating at the high temperatures required by this industry, which are considerably higher than the safe operating limits of prior art blast-furnace hot-blast stoves. In addition to its special field, a stove embodying the invention can be used wherever its type is required.

A specific example of a hot-blast stove constructed according to the principles of this invention, is illustrated by the accompanying drawings, the various figures being as follows:

Figure 1 is a vertical section of the stove;

Figure 2 is a horizontal cross-section from the line II—II in Figure 1 on an enlarged scale; and

Figure 3 is a vertical cross-section from the line III—III in Figure 1 on a still further enlarged scale.

More specifically, these drawings show a vertical substantially cylindrical steel shell 1 supporting a steel dome 2 on its top, this dome 2 having a cylindrical steel side 3 from which two vertically elongated laterally spaced steel ducts 4 extend substantially horizontally with their ends converging and connecting with the cylindrical side 5 of a smaller second steel dome 6 so that this second dome is supported by the first dome 2 which is, in turn, supported by the steel shell 1, the latter, of course, resting on the ground. The ducts 4 function vertically as cantilevers carrying the weight of the dome 6, and function laterally as struts providing lateral rigidity. The ducts 4 provide greater rigidity as cantilevers by reason of being made with vertically elongated cross-sections. This second dome 6 connects through a thermal expansion connection 7 with a second vertical substantially cylindrical steel shell 8 having its own supporting means in the form of a platform 9 on which its bottom rests.

The above construction involves the advantage that thermal expansion vertically is balanced throughout the structure, the two domes 2 and 6 moving vertically as a unit when the shell 1 moves vertically, the shell 8 being unaffected by this movement since it is working through the expansion connection 7, this also meaning that the shell 8 is free to move vertically independently of the shell 1 and the two domes.

Inside the shell 1 is the stove's vertical brick checkerwork 10 with its laterally enclosing vertical brick lining 11, all this brickwork being carried by the stove bottom 12 independently of the shell 1 and being relieved of the weight of the

2

domes 2 and 6 by this shell 1. Thermal expansion space is provided between the outside of the lining 11 and the inside of the shell 1, and there is room inside the dome 2 for all the brickwork to thermally expand without moving this dome. Both the steel domes 2 and 6 support brick linings 13 and 14, respectively, these linings resting on inwardly extending flanges of the cylindrical dome sides 3 and 5, respectively, and thermal expansion spaces being provided between the outsides of the brick linings and the insides of the two steel domes. The interconnecting steel ducts 4 are provided with flat bottoms, straight vertical sides and arched roofs, this permitting them to be lined with standard sized bricks forming arched-topped ducts 15 which constitute brick linings for the steel ducts 4, these brick linings or ducts 15 being built into the linings 13 and 14 so they are also supported by the dome side flanges, and having expansion spaces between their outsides and the insides of the steel ducts at their bottoms, sides and tops.

The second steel dome 6 and its brick lining 14 are much smaller than the steel dome 2 and its brick lining 13, the second steel shell 8 being likewise considerably smaller than the steel shell 1 and containing a brick lining 16 the weight of which is carried by the support 9 and which has its outside spaced from the inside of the steel shell 8 to provide a thermal expansion space. The brick lining 16 of this second cylinder 8 is provided with a burner connection 17 and constitutes the stove's combustion chamber. Thus, the stove is of the external combustion chamber type, the combustion chamber being entirely outside of the checkerwork 10 and the lining 11, and laterally spaced therefrom as an independent unit.

In operation, a burner is connected at the connection 17, and combustion occurs inside the lining 16 in the manner necessary to produce the high temperatures required by the synthetic rubber industry. This introduces no complications because the vertical combustion chamber brick lining 16 can thermally expand without affecting any of the other stove parts, this likewise being true of the combustion chamber steel shell 8. This is important because these are the hottest parts of the stove. The top of the vertical brick lining 16 telescopes inside the bottom of the brick lining 14 of the dome side 5, to an extent sufficient for safety purposes, there being no connection between the two, however.

The combustion products exhaust into the brick lining 14 of the steel dome 6 and travel from there

55

through the brick linings 15 of the ducts 4 so as to introduce parallel horizontal flows of combustion products into the brick lining 13 of the steel dome 2 at positions spaced circumferentially of the side of this lining, the effect being a distributed horizontal introduction of the combustion products into the checkerwork dome so as to avoid local damage, particularly, to the top of the checkerwork. To enhance this protection, the top of the checkerwork is positioned well below the level of the ducts, this, in conjunction with the vertical cylindrical sides of the checkerwork dome, providing a large expansion space for the combustion products. The combustion products then travel evenly down through the checkerwork 10 and out through the bottom of the stove.

During the necessary cyclic operation, the temperature of the checkerwork varies between extremes, but this does not upset the balanced construction of the stove. Thus, the checkerwork 10 and the brick lining 11 may thermally expand without affecting the steel shell 1, and the latter can likewise thermally expand, it carrying both the domes 2 and 6 which can move independently of the steel combustion chamber steel shell 8, by reason of the thermal expansion connection 7. This independence is important because of the temperature differentials, such as those existing between the combustion chamber and checkerwork, for instance. As in the case of the lining 16 in the combustion chamber, the lining 11 extends upwardly into safe telescoping relationship inside the depending lining of the checkerwork dome, the two parts being entirely free for relative movement. In no instance is any of the brickwork required to support anything other than its own weight, and there is no instance where the thermal expansion of the brickwork is restrained in any manner.

It is because of these constructional details which permit the stove to operate as a balanced construction with all of its parts free to thermally expand to the varying extents resulting from their varying temperatures, that the stove can operate safely at the high temperatures required by the synthetic rubber industry. Before closing, attention is called to Patent No. 2,257,453 showing a stove shell and thermal insulation particularly adapted for incorporation in the present invention, this not being illustrated by the drawings in the present instance, to avoid confusion with the fundamentals here involved.

I claim:

1. In a hot blast stove comprising an insulating wall having checker tile mounted therein and

55

having a sheet metal housing spaced from the outer wall thereof, a combustion chamber spaced from said checker tile structure having an insulating wall and a sheet metal lining spaced from the outer wall thereof, domes mounted on the respective checkerwork and combustion chamber structures having communicating ducts laterally spaced to deliver the products of combustion from the combustion chamber over substantially the entire area above the checker tile, said ducts being of a greater horizontal cross-sectional area than the dome above the combustion chamber, said domes and ducts having a sheet metal outer housing connected to the housing of the combustion chamber by a thermal expansion joint whereby the duct connected domes are vertically movable as a unit in response to thermal expansion of the checkerwork wall.

2. In a hot blast stove comprising a checkerwork unit and a combustion unit communicating to deliver the products of combustion to the top of the checkerwork unit, of a plurality of domes mounted on top of said units joined by laterally spaced ducts of greater horizontal cross-sectional area than the dome above the combustion unit, said ducts being spaced to distribute the products of combustion substantially uniformly over the entire area of the checkerwork in the chamber formed by the checkerwork unit dome, the combustion unit dome having thermal expansion connection with the wall of the combustion unit and said checkerwork and combustion unit domes and communicating ducts having sheet metal housings.

3. In a hot blast stove a checkerwork unit and a combustion unit having domes forming chambers at the top thereof communicating through a plurality of laterally spaced ducts, the longitudinal cross-sectional area of which is greater than the dome above the combustion unit and being spaced to distribute the products of combustion substantially uniformly over the entire area at the top of the checkerwork, said checkerwork, combustion unit and domes having refractory linings and sheet metal housings interacting to be independently movable responsive to thermal expansion, the dome and duct structures constituting a monolithic wall with the duct walls functioning vertically as cantilevers carrying the weight of the combustion unit dome to adapt the dome units for thermal movement independently of the checkerwork and combustion unit walls and housings.

ANDREW BOWLAND.
